CLAIM

The ornamental design for a vehicle door as shown and described.

DESCRIPTION

FIG. 1 depicts a front view of a vehicle door showing our new design.

FIG. 2 depicts a back view thereof.

FIG. 3 depicts a right side view thereof.

FIG. 4 depicts a left side view thereof.

FIG. 5 depicts a top view thereof.

FIG. 6 depicts a bottom view thereof.

FIG. 7 depicts a front, left, top perspective view thereof; and, FIG. 8 depicts a front, right, bottom perspective view thereof.

The claimed design is indicated by the relatively dark portions in the figures. The relatively light portions form no part of the claimed design. The dash lines depict boundaries of the claimed design.

1 Claim, 6 Drawing Sheets
